Des. 241,308
Patented Sept. 7, 1976

241,308

PULL PLATE FOR A DOOR

Christopher J. Hoskins, 7205 S. Exchange,
Chicago, Ill. 60649

Filed June 20, 1975, Ser. No. 588,777

Term of patent 14 years

Int. Cl. D8—06

U.S. Cl. D8—146

FIG. 2

FIG. 1

FIG. 3

FIG. 4

FIG. 5

FIG. 1 is a front elevational view of a pull plate for a door showing my new design;

FIG. 2 is an elevational view taken from one side thereof;

FIG. 3 is an elevational view taken from the side opposite that shown in FIG. 2;

FIG. 4 is a top plan view thereof; and

FIG. 5 is a rear elevational view thereof.

I claim:

The ornamental design for a pull plate for a door, as shown.
